UNITED STATES PATENT OFFICE

2,534,983

ATTACHMENT FOR INTERNAL-
COMBUSTION ENGINES

Gerald F. Mooney, Lansing, Iowa

Application January 17, 1947, Serial No. 722,566

1 Claim. (Cl. 123—122)

1

This invention relates to an attachment for internal combustion engines and more especially to a conduit adapted to be interposed between the intake manifold or fuel intake of an internal combustion engine and the carburetor for positioning the carburetor at a more remote position relatively to the engine and for providing a conduit for the fuel mixture and by which said mixture will be conveyed by a circuitous route and subjected to heat from the engine in its travel between the carburetor and intake ports of the cylinders to promote vaporization of the fuel mixture and a more complete combustion of the fuel in the combustion chamber, to thus improve the operating efficiency of the engine and to reduce the fuel consumption thereof.

Various other objects and advantages of the invention will hereinafter become more fully apparent from the following description of the drawings, illustrating a preferred embodiment of the invention, and wherein:

Figure 1 is a side elevational view looking toward the side of an engine, of the internal combustion type, which is disposed remote to the side thereof through which the fuel mixture is admitted to the cylinders;

Figure 2 is a top plan view of the invention as illustrated in Figure 1;

Figure 3 is a side elevational view looking toward the opposite side of Figure 1; and

Figure 4 is an end view in elevation looking from front to rear of the engine.

Referring more specifically to the drawings, for the purpose of illustrating one adaptation of the invention, hereinafter to be described, 5 designates generally the upper portion of an internal combustion engine having an exhaust manifold 6 extending along one side 7 thereof and an intake manifold 8 on the opposite side 9 thereof and which is connected to a plurality of intake ports 10 of said sides 9. A conventional carburetor 11 including a fuel supply line 12 and an air intake passage 13 is shown mounted above and to one side of the engine 5 and adjacent the sides 9 thereof.

Instead of the carburetor 11 being disposed in close proximity to the side 9 and connected at its outlet end 14 to the intake manifold 8, the invention provides a conduit, designated generally 15 having an inlet end 16 which is connected to the bottom or outlet of the carburetor 11 and which extends downwardly therefrom, as best seen in Figure 3. The portion 16 of the conduit 15 merges with the rearwardly extending portion 17 thereof which extends along the side 9 rearwardly and in converging relationship thereto and which is inturned to form the conduit portion 18 which extends across the rear end of the engine 5. The conduit 15 also includes a portion 19 which merges with the opposite end of the portion 18 and which is disposed at substantially a right angle thereto. The portion 19 extends along the side 7 of the engine 5 and is preferably disposed in close proximity thereto

2

and preferably beneath and adjacent the exhaust manifold 6. The forward end of the portion 19 merges with a transverse conduit portion 20 which extends transversely across the forward end of the engine 5 and to beyond the side 9 and which is turned rearwardly to form the conduit portion 21 having an inturned rear end 22, forming the opposite end of the conduit 15 and which is connected to and communicates with the intake manifold 8, preferably intermediate of the ends thereof.

From the foregoing will be readily apparent that the mixture of fuel and air from the carburetor 11 passes through the various portions of the conduit 15 and in the direction as indicated by the arrows 23, by a circuitous route to the intake manifold 8 and therefrom to the intake ports 10 of the engine 5. It will be readily obvious that the fuel mixture will be vaporized in its passage through the conduit 15 due to the distance of its travel between the carburetor and intake manifold and also and more particularly because of the fact that the fuel is subjected to the heat from the engine 5 and its exhaust manifold 6 in passing therearound, so that the fuel mixture will be in a highly vaporized state when admitted to the combustion chambers, not shown, of the engine 5 to thus cause the engine to operate more efficiently and with a considerable saving in fuel consumption.

Various modifications and changes are contemplated and may obviously be resorted to, without departing from the spirit and scope of the invention as hereinafter defined by the appended claim.

I claim:

An attachment for the fuel supply system of an internal combustion engine, comprising a fuel supply conduit adapted to be interposed between the intake port of an engine and the carburetor thereof, said conduit extending substantially entirely around the engine to provide an indirect and circuitous passage for the fuel mixture from the carburetor to the intake port and for subjecting the fuel mixture to the heat radiated from the engine, for thoroughly vaporizing the mixture during its passage from the carburetor to the fuel intake port, said conduit having portions disposed in close proximity to at least one side and both ends of the engine and including a portion disposed longitudinally of and in close proximity to a portion of the exhaust manifold.
